MASK STRUCTURE

James Edward Duggan, Indianapolis, Ind.

Application January 15, 1943, Serial No. 472,517

6 Claims. (Cl. 91—65)

This invention relates generally to devices that are used during painting or plating operations to protect certain portions of articles from paint or plating material applied to adjacent portions thereof, and refers more particularly to masks for preventing paint or plating material from contacting or passing onto the working surfaces of the teeth of bevel gears, bevel pinions and the like when other portions of such gears are painted or plated.

One of the essential objects of the invention is to provide a mask capable of thoroughly protecting the working surfaces of the teeth mentioned without in any way interfering with the painting or plating operation.

Another object is to provide a mask that may be easily and quickly applied to and removed from the portions to be protected without marring or impairing any part of the gears.

Another object is to provide a mask that may be used repeatedly without being scrapped.

Another object is to provide a mask that is simple in construction, economical to manufacture, and efficient in operation.

Other objects, advantages and novel details of construction of this invention will be made more apparent as this description proceeds, especially when considered in connection with the accompanying drawing, wherein:

Figure 1 is an edge elevational view of a mask embodying my invention applied to a bevel gear, with parts broken away and in section;

Figure 2 is a top plan view of the mask;

Figure 3 is a bottom plan view of the mask;

Figure 4 is a vertical cross sectional view through the mask;

Figure 5 is a view similar to Figure 1 but showing an inverted bevel gear provided with the mask embodying my invention.

Referring now to the drawing, A is a ring type bevel gear having an annular body 10 provided on a beveled surface thereof with circumferentially spaced transversely extending helical teeth 11 and having a laterally projecting interiorly splined hub 12, and B is a mask embodying my invention adapted to protect the helical teeth 11 of the gear from paint or plating material applied to other portions of the gear.

In the present instance the gear A is a power gear for an airplane propeller and ordinarily has plating material such as copper plating upon all portions thereof except the teeth 11 which are usually highly polished for proper engagement with the teeth (not shown) of a meshing gear.

In the past, due to the absence from the mar-

ket of a mask such as that forming the subject matter of this application, some manufacturers found it necessary to plate the entire gear including the teeth 11 thereof, and then to return the gear to the machine shop where the plating material on the teeth was removed by a grinding operation. The teeth of the gear were then polished. Thus, such procedure required considerable time, labor and material and has proven unsatisfactory. For example, during the grinding operation or other handling of the gear back and forth, one or more portions of the plating material on the body of the gear were sometimes accidentally removed or otherwise damaged. Moreover, the plating material removed by the grinding operation from the teeth of the gear was usually wasted. Ordinarily the plating material was applied to the whole gear before it was subjected to the usual hardening operation, hence additional handling of the gear was required before the plating material on the teeth thereof was subjected to the grinding operation mentioned.

To avoid the objections of the procedure just described other manufacturers covered the teeth only of the gear with wax before the other portions thereof such as the body 10 and hub 12 were plated or painted. Ordinarily this wax coating or covering was obtained by dipping the teeth of the gear in hot wax in a suitable container, then withdrawing the wax covered teeth from the container, and then allowing the wax to cool and harden on the teeth. However such dipping operations were by no means accurate, hence portions of the body 10 or hub 12 to be plated were sometimes accidentally covered by the wax intended for the teeth only. This necessitated the removal of the wax from the body or hub of the gear before it could be plated. Moreover, the wax sometimes did not remain on the teeth during the plating or painting operation, hence the exposed portions of the teeth received accidentally deposits of plating material or paint that had to be removed as aforesaid. Accordingly, this procedure was likewise unsatisfactory.

In the present instance, however, I have overcome entirely the objections mentioned by the provision of a one piece mask B that may be easily and quickly applied to a gear to accurately and effectively protect the teeth 11 thereof from paint or plating material applied to other portions of the gear. Preferably this mask B is in the form of a dished annulus having a circumferentially extending channel 13 within the

dished portion thereof for receiving the teeth 11 of the gear, and is preferably made of resilient material such as rubber or rubber composition. As shown, the mask B has an annular body 14 inclined outwardly and downwardly relative to the axis thereof and provided at the upper and lower edges thereof with inwardly projecting substantially parallel or concentric annular flanges 15 and 16, respectively, and provided on the underside of the body 14 between said flanges with circumferentially spaced transversely extending helical webs 17. Preferably these webs 17 increase slightly in depth from the upper flange 15 to the lower flange 16 and are terminally connected thereto. To insure a tight seal with the body 10 of the gear, the flanges 15 and 16 are provided at their inner edges with circumferentially extending inturned angular clamping lips 18 and 19, respectively.

In use, when the mask B is applied to the gear A, as illustrated in Figure 1, the body 10 of the gear is received between the flanges 15 and 16 on the underside of the body 14 of the mask, so that the helical teeth 11 of the gear are received in the helical grooves 20 that are provided in the mask between the helical webs 17 thereof. Likewise, the helical webs 17 of the mask fit snugly between the helical teeth 11 of the gear, while the clamping lips 18 and 19 of the mask bear firmly against and provide knife-like annular edges at opposite sides of the body 10 of the gear. As a result, the mask B covers and protects the helical teeth 11 of the gear A against paint or plating material applied to the other portions of the gear without interfering with the application of plating material or paint to such other portions.

Thus, from the foregoing, it will be apparent that the entire gear A may be completely machined, finished and polished before being plated or painted because the mask B effectively protects the working surfaces of the teeth 11 thereof and may be applied to the gear after it is polished without marring the finish thereof, and may be removed from the gear after the painting or plating operation has been completed without marring the plating material or paint that has been applied to the gear. Moreover, the same mask B may be used over and over again as aforesaid on different gears without being scrapped. As a result, a substantial saving in time, labor and material is effected.

When the mask B is used, the gear A protected thereby may be subjected before or after the plating or painting operation to the usual hardening operation to complete it for the market.

In Figure 5 I have illustrated an inverted bevel gear 30 having helical teeth 31 that are protected by a similar mask B'. In this construction, the mask B' is slipped down the shaft 32 onto the bevel gear 30 and is engaged with the latter as in Figure 1.

What I claim as my invention is:

1. A mask for protecting the working surfaces of the teeth of a bevel gear from plating material, paint and the like applied to other portions of said gear, comprising a solid dished annulus of resilient material having a circumferentially extending channel within the dished portion there-

of for receiving the teeth of said gear, the base of the channel being provided between opposite sides of the channel with circumferentially spaced transversely extending webs for masking engagement with the working surfaces of the teeth of said gear, opposite sides of said channel being provided at the free edges thereof with circumferentially extending inwardly directed lips for sealing engagement with the gear upon opposite sides of the teeth thereof.

2. A mask of the class described formed entirely of resilient material and comprising a one piece solid annulus having a dished portion provided with a circumferentially extending channel, the base of said channel being provided between opposite sides thereof with circumferentially spaced transversely extending webs.

3. A mask of the class described formed entirely of resilient material and comprising a one piece solid annulus having a dished portion provided with a circumferentially extending channel, the base of said channel being provided between opposite sides thereof with circumferentially spaced transversely extending webs, opposite sides of the channel being provided at the free edges thereof with circumferentially extending inturned clamping lips.

4. Means for protecting the teeth of a bevel gear from paint or plating material while such paint or plating material is applied to other portions of said gear, comprising a one-piece annular masking element formed entirely of resilient material and having a circumferentially extending channel for receiving the teeth and adjacent body portion of said gear and provided within said channel between opposite sides thereof with circumferentially spaced transversely extending webs for meshing engagement with the teeth of said gear.

40 5. Means for protecting the teeth of a bevel gear from paint or plating material while such paint or plating material is applied to other portions of said gear, comprising a one-piece annular masking element formed entirely of resilient material and having a circumferentially extending channel for receiving the teeth and adjacent body portion of said gear and provided within said channel between opposite sides thereof with circumferentially spaced transversely extending webs for meshing engagement with the teeth of said gear, opposite sides of the channel being provided at the inner edges thereof with means for sealing engagement with the body portion of said gear.

55 6. Means for protecting the teeth of a bevel gear from paint or plating material while such paint or plating material is applied to other portions of said gear, comprising a one-piece annular masking element formed entirely of resilient material and having a circumferentially extending channel for receiving the teeth and adjacent body portion of said gear and provided within said channel between opposite sides thereof with circumferentially spaced transversely extending webs for meshing engagement with the teeth of said gear, opposite sides of the channel being provided at the inner edges thereof with circumferentially extending inturned clamping lips for sealing engagement with the body portion of said gear.

JAMES EDWARD DUGGAN.
